(57) **CLAIM**

The ornamental design for a sensor console, as shown and described.

DESCRIPTION

FIG. 1 is a front, top, and left side perspective view of the sensor console showing the new design according to a first implementation.

FIG. 2 is a rear, bottom, and right side perspective view of the sensor console showing the new design according to the first implementation.

FIG. 3 is a top view of the sensor console showing the new design according to the first implementation.

FIG. 4 is a bottom view of the sensor console showing the new design according to the first implementation.

FIG. 5 is a left side view of the sensor console showing the new design according to the first implementation.

FIG. 6 is a right side view of the sensor console showing the new design according to the first implementation.

FIG. 7 is a front view of the sensor console showing the new design according to the first implementation.

FIG. 8 is a rear view of the sensor console showing the new design according to the first implementation.

FIG. 9 is a front, top, and left side perspective view of the sensor console showing the new design according to a second implementation.

FIG. 10 is a rear, bottom, and right side perspective view of the sensor console showing the new design according to the second implementation.

FIG. 11 is a top view of the sensor console showing the new design according to the second implementation.

FIG. 12 is a bottom view of the sensor console showing the new design according to the second implementation.

FIG. 13 is a left side view of the sensor console showing the new design according to the second implementation.

FIG. 14 is a right side view of the sensor console showing the new design according to the second implementation.

FIG. 15 is a front view of the sensor console showing the new design according to the second implementation; and, FIG. 16 is a rear view of the sensor console showing the new design according to the second implementation.

Within the drawings, the straight-line surface shading and stippling show the character and contour of the surfaces in the claimed design of the sensor console. The broken lines show unclaimed portions of the sensor platform, and thus form no part of the claimed design.

1 Claim, 10 Drawing Sheets
